UNITED STATES PATENT OFFICE

150,545

DESIGN FOR A VEGETABLE MASHER

David H. Bergstedt, Melvindale, Mich.

Application February 20, 1947, Serial No. 137,048

Term of patent 7 years

(Cl. D89—1)

To all whom it may concern:

Be it known that I, David H. Bergstedt, a citizen of the United States, residing at Melvindale, in the county of Wayne and State of Michigan, have invented a new, original, and ornamental Design for a Vegetable Masher, of which the following is a specification, reference being had to the accompanying drawing, forming part thereof.

I claim:

The ornamental design for a vegetable masher, as shown.

DAVID H. BERGSTEDT.
